FIG. 1

FIG. 2

FIG. 2

FIGURE 1 is a front elevational view of a building showing my new design;

FIG. 2 is a rear elevational view with a portion of the fence broken away to show the structural configuration of the building of my design;

FIGURE 3 is a side elevational view thereof, both sides of which are identical; and

FIGURE 4 is a top plan view.

The dominant features of my design for a building reside in the portions that are identified in full lines.

I claim:

The ornamental design for a building, as shown and described.
